UNITED STATES PATENT OFFICE.

FRIEDRICH DÖRSING, OF ISERLOHN, GERMANY, ASSIGNOR TO THE FIRM OF F. SOENNECKEN,
OF BONN, GERMANY.

DEVICE FOR GRINDING WRITING-PENS.

No. 900,271.

Specification of Letters Patent.

Patented Oct. 6, 1908.

Application filed September 30, 1907. Serial No. 395,111.

To all whom it may concern:

Be it known that I, FRIEDRICH DÖRSING, a subject of the King of Prussia, and resident of Iserlohn, in the Province of Westphalia, 5 German Empire, have invented a new and useful Device for Grinding Writing-Pens, of which the following is an exact specification.

This invention relates to machines for 10 grinding writing pens of the kind in which the pens are held in resiliently mounted holders carried on a rotating wheel. In such pen grinding machines it has been proposed to mount the holders rotatably on the face 15 of the rotating carrier but such arrangements involve a complication of the parts because it was necessary to provide means for rotating the pen so as to bring all parts of its curved back in contact with the grinding wheel.

The object of the present invention is to 20 avoid this complication.

In the machine according to the present invention the pen is resiliently held between 25 jaws formed at one end of a lever centrally pivoted on a bracket on the circumference of the carrier wheel. A curved bow spring coöperates with a stop engaging the circumference of the carrier to hold the pen in 30 position for grinding. The curved spring however can yield to a sufficient extent to bring the pen at all points in its curved back in contact with the grinding wheel and in this way it is not necessary to provide gearing 35 for rotating the pen.

In order to make my invention better understood same is accompanied by a drawing, which shows the construction of this device by way of example.

On the drawings: Figure 1 represents a 40 side view of the whole device; Fig. 2 is a plan view of same; Fig. 3 represents a section on line A—A of Fig. 1; Fig. 4 shows a section on line B—B of Fig. 1; Fig. 5 shows 45 in a side-view an enlarged detail of the pen-holder itself. Fig. 6 is a plan view of this holder and Fig. 7 a front-view of same.

The appliance which holds the pens consists of a wheel *a*, the shaft *k'* of which is 50 journaled into the two pillow-blocks *k*². This pen wheel *a* is set in motion by means of a worm gearing, consisting of the worm wheel *b* and a long shaft *b'*. The latter is at the other side provided with a set of gears 55 *c*, which connect it to the main driving

shaft *c*. The latter is rotated by means of a belt-pulley *c'*. Attached to the one end of the main shaft *c* there is a rope disk *d*, which by means of a rope *d'* transmits the rotation to the small disk *d*², attached to the shaft *e'* of the grinding wheel *e*. The position of the latter can be adjusted to a certain extent in the direction of its shaft *e'* by loosening the set pin *e*⁴ and sliding the grinding wheel to the desired position then 65 fixing the grinding wheel by tightening up the set screw *e*⁴. At the same time the pillow-blocks *e*² of this wheel *e* is movably attached to the foundation-block *c*³ in such a manner as to enable a raising and lowering 70 of its position. This is effected by turning the handle *e*⁴ which by means well known—a wedge and a screw—cause the raising and lowering of the pillow block.

On the surface of the pen wheel *a* there 75 are attached a number of pen holders consisting of the body *f* and a flat spring *f'* placed on the top. The body part *f* is pivotally attached to bolt *f*², which bolt is journaled in a projecting lug *a'*, attached to the main-frame of pen wheel *a*. The body part *f* is provided with a semi-circular piece *f*³, while a block *f*⁴ is attached to the flat spring *f'*. This block contains another semi-circular piece *f*⁵, which represents the counterpart to *f*³, these two pieces being opposite one another and are exactly fitting one 80 on top of the other. Between these two pieces the pen is stuck. On the opposite side of the holder a set-screw *g* is placed. Furthermore there is a curved flat spring *g'* provided for, which is fastened at *g*² to the frame of wheel *a* and at *g*³ to the lug *f*. This curved flat spring has the tendency to 85 turn the pen holder clockwise, so that the holder is forced against the circumference of the frame of wheel *a* and hits against the latter by means of the set-screw *g*. The body part *f* of the pen holder appliance is forked. (See Figs. 4 and 7.) At the place 90 where the prongs unite there is a bolt *x* the head *x'* of which hits against a lever *u*. This lever is pivoted at *u'* to the wheel *a* and provided with a roll *t* at its extreme end. This roll slides on the circumference 95 of a disk *s*, which disk is placed next to the pen wheel *a*. The disk *s* is provided with groove *s'*, as will be seen on Fig. 4, the roll *t* sliding within this groove. The form 100 of the disk is constructed like a cam, con-

sisting of two portions, of which the one s^2 has the smaller and s^3 the larger diameter. Both portions unite at the points s^4 and s^5 . As the roll t in sliding on the circumference of the cam leaves the portion s^2 at point s^6 , it is forced to make an upward motion together with the lever u , which in turn hits the bolt head x' and pushes the bolt upward under compression of spring w , whereby the 10 rounded-off bolt end of x strikes against the lower side of the holder part f^4 . This motion opens the holder, so that the grip of same on the pen relaxes and the latter drops out. As long as the roll t slides over the elevated 15 cam-part s^3 the pen holder remains open, which furnishes sufficient time to replace a new pen into the holder. As the roll t slides over point s^4 it drops to the lower part s^2 of the cam s , and in turn lever u and bolt x follow suit, whereby the pen-holder shuts itself. The parts f^3 and f^5 holding the pens, are 20 made exchangeable and may be disposed across the surface of pen wheel α , an arrangement as is shown in Fig. 1, or tangentially to the surface of this wheel, as is indicated on Fig. 4. This pen-holder-appliance however may be provided with two of such pen grips each, of which one is arranged across and one tangentially to the pen-wheel. 25

30 The working of the apparatus is as follows: The whole device is actuated from the main shaft e , which puts the grinding wheel e as well as the pen-wheel α in motion. In case the pen holder devices are arranged 35 across the wheel e , as is shown in Fig. 1, the pens to be ground are placed into same before they reach the grinding wheel e . Thus the pens are connected to the grinding 40 wheel in a manner, whereby the edge of each pen strikes the wheel first and while passing by a grinding of the pen takes place over its entire breadth. This is made possible on account of the flexibility of the pen holder appliance given to it by the 45 way the main spring g' is fastened. For each holder is swinging back as the pen passes the grinding wheel e and in doing so has to overcome a certain counter- 50 action of spring g' . As soon as the pen leaves the grinding wheel the spring g' will force the pen-holder back to its original position of rest, which is determined by the set screw y . After the grinding manipulation the pens 55 are withdrawn from the holders, but if the roller t strike the point s^5 of the cam s the pens are dropped automatically, inasmuch as each holder is then opened by the bolt x striking against the lower side of pen-holder part f^4 . If the pens are to be ground length- 60 wise they are replaced into the holders tangentially to the pen-wheel e and as a matter of course, the pen holder appliances have to be disposed in a similar position. The 65 grinding wheel e is then to be shifted until it comes into the path of the rotating pen.

For such grinding purposes it will be most practical to provide the grinding wheel with the grooved grinding surface, in order to make the latter touch each part of the curved surface of the pen.

Having thus fully described the nature of my invention, what I desire to secure by Letters Patent of the United States is:—

1. In a pen grinding machine, a grinding wheel, a rotating pen holder carrier, means for bringing all points of the curved surface of the pen evenly in contact with the grinding wheel comprising, spring pressed pivoted pen holding jaws.

2. In a pen grinding machine, a grinding wheel, a rotating pen holder carrier, means for bringing all points of the curved surface of the pen evenly in contact with the grinding wheel comprising, pivoted pen holder jaws, curved bows springs holding said pen- holding jaws resiliently.

3. A pen grinding machine, having in combination, a grinding wheel, a carrier wheel, pen holding jaws pivotally carried on the circumference of said wheel about axes 90 parallel to the axis of the carrier wheel, a bow spring pressing said penholding jaws radially outward for the purpose set forth.

4. A pen grinding machine having in combination, a grinding wheel, a carrier wheel, centrally pivoted penholding jaws carried on the circumference of said wheel about axes parallel to the axis of the carrier wheel, bow springs pressing said penholding jaws radially outwards at one end, stop pins on the opposite end of said centrally pivoted jaws to the penholding side and co-acting with the circumference of the carrier wheel to limit the motion of the jaws, substantially as described.

5. A pen grinding machine having in combination, a grinding wheel, a carrier wheel, pivots mounted on the circumference of said carrier wheel and parallel to the axis thereof, penholding jaws carried on said pivots and comprising a pivoted inner jaw part, an outer jaw part, a band spring holding said outer to said inner jaw part together with a bow spring resiliently pressing said inner jaw part radially outwards.

6. A pen grinding machine having in combination, a grinding wheel, a carrier wheel, pivots on the circumference of the pivot wheel and parallel to the axis thereof, penholding jaws carried on said pivots and comprising a pivoted inner jaw part, an outer jaw part, said jaw parts being provided with axially and tangentially arranged, gripping parts, a band spring holding said outer to said inner jaw part together with a bow spring resiliently pressing said inner jaw part radially outwards at the penholding end.

7. A pen grinding machine having in combination, a grinding wheel, a carrier wheel,

pivots mounted on the circumference of said carrier wheel and parallel to the axis thereof, pen holding jaws carried centrally on said pivots and comprising a pivoted inner 5 jaw part with an opening therein at the pen-holding side, an outer jaw part, a band spring holding said outer to said inner jaw part together with a bow spring resiliently 10 pressing said inner jaw part radially outwards and means operating through the opening in the inner jaw part for pressing the outer jaw part radially outwards and thereby releasing the pen.

8. A pen grinding machine having in combination, a grinding wheel, a carrier wheel, brackets projecting radially from the circumference of said carrier wheel, pivots in said brackets arranged parallel to the carrier wheel axis, holding jaws carried centrally by said pivots, spring pressing means 15 acting to press said penholding jaws radially outwards at one end.

9. A pen grinding machine having in combination, a grinding wheel, a carrier wheel, 20 brackets projecting radially from the circumference of said carrier wheel, pivots in said brackets arranged parallel to the carrier wheel axis, holding jaws carried centrally by said pivots, a bow spring fixed at one end to the carrier wheel and at its other 25 end to the holding jaws so as to press said jaws radially outwards at one end.

10. A pen grinding machine having in combination, a grinding wheel, a carrier 30 wheel, brackets projecting radially from the circumference of said carrier wheel, pivots in said brackets arranged parallel to the car-

rier wheel axis, holding jaws carried centrally by said pivots, spring pressing means acting to press said penholding jaws radially 40 outwards at one end, means for releasing said holding jaws comprising pins movable in the plane of the carrier and cam operating means for said pins.

11. A pen grinding machine having in 45 combination, a grinding wheel, a carrier wheel, brackets projecting radially from the circumference of said carrier wheel, pivots in said brackets arranged parallel to the carrier wheel axis, holding jaws carried centrally by said pivots, a bow spring fixed at one end to the carrier wheel and its other end to the holding jaws for pressing the same radially outwards at one end, means for releasing said jaws comprising spring held 50 pins slidable in the carrier, pivoted levers on the carrier engaging said pins and a fixed cam with which said levers engage.

12. In a pen grinding machine, penholding jaws comprising a pivotally carried jaw 55 part with semi-circular projections (f^3) at right angles to each other thereon, further jaw parts each in the form of a plate having semi-circular recesses engaging over said semi-circular projections, a flat spring carrying said further jaw plate at one end and fixed to the first mentioned jaw part at the other end.

In witness whereof I have hereunto set my hand in the presence of two witnesses.

FRIEDRICH DÖRSING.
